UNITED STATES PATENT OFFICE.

EDWARD WM. EDWARDS, OF CINCINNATI, OHIO.

SHEET-METAL ROOFING.

1,137,746.

Specification of Letters Patent.

Patented May 4, 1915.

Application filed September 25, 1914. Serial No. 863,516.

To all whom it may concern:

Be it known that I, EDWARD W. EDWARDS, a citizen of the United States of America, and a resident of Cincinnati, county of 5 Hamilton, State of Ohio, have invented certain new and useful Improvements in Sheet-Metal Roofing, of which the following is a full and clear specification, reference being had to the accompanying drawings, in 10 which—

Figure 1 is a perspective view showing a series of the sheets interlocked; and Fig. 2 is a transverse sectional view enlarged of the interlocking edges of two adjacent sheets. 15 The object of this invention is to provide an interlocked joint between adjacent sheets which shall have a high degree of efficiency as a barrier against ingress of water to the roofing boards below the sheets and which at 20 the same time shall be rigid enough to avoid being seriously indented by persons walking on the roof, as more fully hereinafter set forth.

Referring to the drawings by reference 25 numerals, 2 designates the main part of the sheet and 3 designates an upstanding rounded ridge formed along one extreme edge of the sheet by bending up the metal in the form of a bead, this bead or ridge being approximately semi-circular in cross section.

Near the other edge of the sheet, the metal is folded longitudinally upon itself and the folded parts are brought together and bent over toward the adjacent edge of the sheet, 35 thereby forming a double-thickness, arch-like ridge 4 extending the full length of the sheet, this ridge being approximately semi-circular in cross section and having its free rounded edge 4' terminating near the body 40 of the sheet. That portion of the sheet beyond the edge 5 of the aforesaid ridge is employed as usual as a nailing flange, and directly under the arch-like ridge 4 the metal of the sheet is bent upwardly to form a longitudinal ridge 6, whose upper edge is 45 rounded to conform approximately to the concave lower surface of the ridge 4.

In the enlarged view in Fig. 2, the manner in which the adjacent edges of adjacent 50 sheets interlock is illustrated. It will be seen that the sheets are interlocked by simply slipping the beaded edge 3 of one

sheet into the semi-circular channel formed between the parts 4 and 6, so that when the parts are thus interlocked a single composite 55 ridge is formed throughout the length of the sheet, which is constituted of four thicknesses of metal, thereby providing an interlocking connection which will be firm enough to prevent being seriously indented 60 by persons walking on the roof and which at the same time will be so constructed as to permit a maximum of expansion and contraction without disconnecting the interlocked folds. This form of interlocking is advantageous also in that it forms such a circuitous passage for any water that might seep or work its way through the joint to the roofing boards that leakage can occur 65 at the joint only by a prolonged flooding of 70 the joint.

It will be seen that the curvature of the bead 3 is different from the curvature of the channel between the parts 4 and 6, and that the free edge of the bead 3 bears upon the 75 sloping inner side of the bead 6; this is advantageous in that it provides for a wedging joint between the member 3 and the two members 4 and 6, whereby a close joint is maintained between these members at all 80 times. This joint will tend to prevent leakage by capillary attraction, this tendency to leakage through capillary action being a very potent force in causing roofs of this type to leak. It is advantageous to have 85 the upper or convex side of the bead 3 abut against the under side of the convex part 4, as by that abutment the free edge of the bead 3 is kept pressed against the sloping convex side of the bead 6, as shown, the bead 90 3 being slightly spread when it is inserted in the semi-circular channel.

Having thus described my invention, what I claim is:

A sheet metal roofing plate, embodying a 95 nailing flange along one edge and an upstanding longitudinal ridge formed adjacent thereto and a double walled ridge formed by bending the metal upon itself and then bending the same over said ridge leaving a space 100 therebetween, said ridges lying in close relation throughout so that said space therebetween will be relatively narrow, and a bead on the extreme opposite side edge of

the plate formed by bending up the edge thereof, the shape of said bead being such as to cause it to fit in the space between the ridges of the adjacent plate and have its free depending edge wedge against the inner sloping wall of said upstanding longitudinal ridge.

In testimony whereof I hereunto affix my signature in the presence of two witnesses.

EDWARD WM. EDWARDS.
